WALL STRUCTURE

Gustav H. Kaemmerling, Erie, Pa., assignor to
Erie City Iron Works, Erie, Pa., a corporation
of Pennsylvania

Application October 17, 1932, Serial No. 638,065

17 Claims. (Cl. 122—6)

The present wall structure is particularly designed for use with tubes in forming such wall structures as are commonly called water walls. In many furnace structures some walls at least 5 are formed by arranging a series of tubes in the general plane of the wall and facing these tubes with blocks, metal blocks being commonly used. It is desirable to maintain the tubes in substantially a constant relation, usually parallel and 10 to at the same time, thoroughly secure the different blocks in contact with the tubes so that there may be a ready heat exchange between the blocks and tubes. The present invention accomplishes these desirable features in a simple and 15 efficient manner. Features and details of the invention will appear from the specification and claims.

Preferred embodiments of the invention are 20 illustrated in the accompanying drawings as follows:—

Fig. 1 shows a rear view of a portion of a water wall.

Fig. 2 a front view of a portion of a water wall.

Fig. 3 a section on the line 3—3 in Fig. 2.

Fig. 4 a rear view of one of the wall blocks.

Fig. 5 a top, or edge view of one of the blocks.

Fig. 6 a rear view of a portion of a wall showing an alternative construction.

Fig. 7 a section on the line 7—7 in Fig. 6.

Fig. 8 a rear view of a portion of a wall showing a further modification.

Fig. 9 a front view of the wall shown in Fig. 8.

Fig. 10 a section on the line 10—10 in Fig. 8.

Fig. 11 a modified structure in section on the 35 line 11—11 in Fig. 12.

Fig. 12 an elevation of the modification.

Fig. 13 shows a modification in section on the line 13—13 in Fig. 14.

Fig. 14 shows an elevation of the same modification.

1 marks the tubes. These are usually in parallel relation and usually vertical, or at least may be upright. 2 marks the blocks shown in Figs. 1 to 5. Each of these blocks is provided with a pair 45 of grooves 3, the grooves forming seats for the tubes. Each block has a threaded opening 4 receiving a screw 5 extending from a clamping plate 6, the clamping plate resting on adjacent tubes.

The wall is arranged with joints 7, these joints 50 being between the tubes and are preferably staggered, or off-set, as clearly indicated in Fig. 2. In this way each pair of adjacent tubes is seated in some grooves associated in the same blocks, so that the tubes of each pair are tied together in 55 each alternate row of blocks. The association of a plurality of grooves in each block is effective in tying the tubes in proper relation, particularly where the blocks are arranged in staggered relation so that there is a single block bridging 60 and embracing each pair of tubes.

This structure has many advantages over what is more commonly used. In the structures more commonly used the blocks forming the wall have their ends terminating in the fronts of each pair of tubes, so that as the block is clamped to its seat the side surfaces of these blocks which are under-cut to engage the walls of the tube tend to spread the tubes and in order to hold the tubes and the wall in shape greater dependence must be given to the shape of the clamps. With 10 the present invention the blocks having the associated tube embracing grooves avoid any tendency to separate the tubes, but on the contrary tie them together. The structure also permits of the use of a wide variety of clamps as the embracing 15 action of the blocks accomplishes some of the functions which are sometimes performed by the clamps.

In Figs. 6 and 7 the blocks are similar to those 20 shown in Figs. 4 and 5 except that there are two openings 8 and 9 instead of the single opening 4 and T-shaped bars 10 extend entirely across the wall and bolts 11 extend through these bars into the screw-threaded openings 8 and 9 for securing the blocks in place.

In the structure shown in Figs. 8, 9, and 10, the blocks 12 are each provided with three 25 grooves 13, thus engaging three tubes and the joints between the ends are staggered so that they are distributed between the tubes so that a break between any two tubes occurs only in every third row of blocks. The blocks are provided with screw-threaded openings 14 and clamps 15 are arranged over each tube with relation to each block. The ends of these clamps are secured to the block by screws 16.

Under some conditions it may be desirable to 30 limit the number of tubes which are definitely tied together by the wall system. This may be accomplished by so forming the wall blocks as to form the wall in panels, each panel involving a group of tubes definitely tied and associated together, but separated from the adjacent panel. In Figs. 11 and 12 one modification carrying out 35 this structure is shown. A panel 17 associates a series of tubes. Some of the blocks 18 may be of normal size embracing a number of tubes, whereas other blocks 19 supplementing the blocks 18 in width associate the remaining tubes of the panel. By making some of the blocks shorter than others the breaks between the blocks may be staggered so that all the tubes of a panel may be tied together in the manner heretofore described with relation to the entire wall.

In the modification shown in Figs. 13 and 14 45 the panels 20 are formed by utilizing blocks 21 which have a length equal to the width of the panels so that all the tubes of the group forming the panel are embraced by each block.

It will be noted that various forms of secur- 50

ing the tubes in place are shown, as for instance in Figs. 8 and 13. In Fig. 19 small blocks are interposed between the tubes and the clamping bars as distinguished from the structure shown in Fig. 13.

What I claim as new is:—

1. In a wall structure, the combination of a series of tubes; and wall blocks each having a plurality of tube-embracing grooves, the walls of each groove engaging opposite sides of the tube embraced and forming seats for the tubes, the joints in each alternate row being off-set and arranged between the tubes, said blocks being associated edge to edge to form a wall. 5
2. In a wall structure, the combination of a series of tubes; and wall blocks each having a plurality of tube-embracing grooves, the walls of each groove engaging opposite sides of the tube embraced and forming seats for the tubes, the joints between the ends of the blocks being between the tubes, said blocks being associated edge to edge to form a wall. 10
3. In a wall structure, the combination of a series of tubes; and wall blocks each having a plurality of tube-embracing grooves, the walls of each groove engaging opposite sides of the tube embraced and forming seats for the tubes, each pair of adjacent tubes being seated in some grooves associated in the same blocks, said blocks being associated edge to edge to form a wall. 15
4. In a wall structure, the combination of a series of tubes; and wall blocks each having a plurality of tube-embracing grooves, the walls of each groove engaging opposite sides of the tube embraced and forming seats for the tubes, each pair of adjacent tubes being seated in some grooves associated in the same blocks, the tubes of each pair of adjacent tubes being also seated in grooves of separate blocks, said blocks being associated edge to edge to form a wall. 20
5. In a wall structure, the combination of a series of tubes; and wall blocks each having a plurality of tube-embracing grooves, the walls of each groove engaging opposite sides of the tube embraced and forming seats for the tubes, the ends of the blocks being off-set in different rows of blocks, said blocks being associated edge to edge to form a wall. 25
6. In a wall structure, the combination of a series of tubes; and wall blocks each having a plurality of tube-embracing grooves, the walls of each groove engaging opposite sides of the tube embraced and forming seats for the tubes, said blocks being arranged in rows with the joints between the ends of the blocks between the tubes and off-set in different rows of blocks, said blocks being associated edge to edge to form a wall. 30
7. In a wall structure, the combination of a series of tubes; and wall blocks each having a pair of tube-embracing grooves, the walls of each groove engaging opposite sides of the tube embraced and forming seats for the tubes, said blocks being associated edge to edge to form a wall. 35
8. In a wall structure, the combination of a series of tubes; and wall blocks each having a pair of tube-embracing grooves, the walls of each groove engaging opposite sides of the tube embraced and forming seats for the tubes, the joints in each alternate row being off-set, said blocks being associated edge to edge to form a wall. 40
9. In a wall structure, the combination of a series of tubes; and wall blocks each having a pair of tube-embracing grooves, the walls of each groove engaging opposite sides of the tube embraced and forming seats for the tubes, the joints in each alternate row being off-set and arranged between the tubes, said blocks being associated edge to edge to form a wall. 45
10. In a wall structure, the combination of a series of tubes; and wall blocks, each block having more than two tube-embracing grooves, the walls of each groove engaging opposite sides of the tube embraced and forming seats for the tubes, said blocks being associated edge to edge to form a wall. 50
11. In a wall structure, the combination of a series of tubes; and wall blocks, each block having more than two tube-embracing grooves, the walls of each groove engaging opposite sides of the tube embraced and forming seats for the tubes, the joints being off-set and distributed between the different pairs of adjacent tubes, said blocks being associated edge to edge to form a wall. 55
12. In a wall structure, the combination of a series of tubes; wall blocks each having a plurality of tube-embracing grooves, the walls of each groove engaging opposite sides of the tube embraced and forming seats for the tubes; and clamps engaging the rear of the tubes for securing the blocks, said blocks being associated edge to edge to form a wall. 60
13. In a wall structure, the combination of a series of tubes; wall blocks each having a plurality of tube-embracing grooves, the walls of each groove engaging opposite sides of the tube embraced and forming seats for the tubes; and clamps engaging a pair of tubes securing each block, said blocks being associated edge to edge to form a wall. 65
14. In a wall structure, the combination of a series of tubes; wall blocks each having a plurality of tube-embracing grooves, the walls of each groove engaging opposite sides of the tube embraced and forming seats for the tubes; and clamps securing the blocks, each clamp extending partially around a single tube and being secured at each end to the block, said blocks being associated edge to edge to form a wall. 70
15. In a wall structure, the combination of a series of tubes; wall blocks each having a plurality of tube-embracing grooves, the walls of each groove engaging opposite sides of the tube embraced and forming seats for the tubes; clamps in the form of flat bars extending across the back of the tubes; and clamping means connecting the bars with the blocks, said blocks being associated edge to edge to form a wall. 75
16. In a wall structure, the combination of a series of tubes; and groups of wall blocks tying groups of tubes together in panels, the blocks having associated tube-embracing grooves, the walls of each groove engaging opposite sides of the tube embraced and coupling the tubes of each panel together, said blocks being associated edge to edge to form a wall. 80
17. In a wall structure, the combination of a series of tubes; and groups of wall blocks tying groups of tubes together in panels, some of the blocks at least having a length equal to the length of a panel and provided with tube-embracing grooves embracing a plurality of tubes, the walls of each groove engaging opposite sides of the tube embraced and the wall blocks being associated edge to edge to form a wall. 85
